UNITED STATES PATENT OFFICE.

FRANK G. METCALF, OF SANDY HOOK, CONNECTICUT.

INSULATING RAIL CONNECTION FOR METAL TIES.

Application filed May 26, 1928. Serial No. 280,705.

This invention relates to improvement in metal tie and rail connections and particularly to connections of such character as will insulate and cushion the rail from the tie.

5 The object of this invention is to produce a simple, strong and durable insulating rail-connection for metal ties constructed with particular reference to silence under traffic and to immunity to excessive strains and damage from the effects of temperature changes, etc.

With this object in view my invention consists in an insulating rail-connection for metal ties having certain details of construction and combinations of parts as will be hereinafter described and particularly recited in the claims.

In the accompanying drawings:

Fig. 1 is a broken top or plan view of one end of a metal tie and a section of rail, showing my improved insulating rail-connection;

Fig. 2 is a side view thereof;

Fig. 3 is a longitudinal sectional view on the line 3—3 of Fig. 1;

25 Fig. 4 is a corresponding view on the line 4—4 of Fig. 1;

Fig. 5 is a transverse sectional view on the line 5—5 of Fig. 2;

30 Fig. 6 is a detached perspective view of the rail-supporting plate;

Fig. 7 is a corresponding view of the insulating cushion-block; and

Fig. 8 is a top or plan view of one of the rail-clips detached.

35 In carrying out my invention as herein shown, I employ a trough-shaped sheet-metal tie 10 having the upper edges of its side walls 11 turned outward to form stiffening flanges 12 upon the upper face of which near the end 40 of the tie I position a rail-supporting plate 13 which spans the gap between the respective side walls 11 and is secured at its corners to the said flanges 12 by means of rivets 14.

The central portion of the rail-plate 13 is struck downward to form a shallow oblong pocket 15 depending between and extending lengthwise with respect to the side walls 11 of the tie and designed for the reception of a correspondingly-shaped block 16 of wood or other suitable insulating and cushioning material. The respective opposite ends of the rail-supporting plate 13 are turned downward between the side walls 11 of the tie to form complementary legs 17 which snugly engage the said side walls 11 and the bottom 18

of the tie so as to assist in bearing the load and in stiffening the tie-structure.

Extending transversely across and resting upon the upper face of the block 16 about midway the length thereof I position the rail 19 which is anchored in place by means of four corresponding rail-clips 20 substantially U-shaped in cross-section and having their side flanges 21 formed with a plurality of notches 22 into which the lateral edges of the base 23 of the rail 19 extend, as clearly shown in Figs. 2 and 3.

The outer end of each of the four rail-clips 20 above mentioned is struck upward to form a shallow downwardly-facing pocket 24 to receive a domical boss 25 offsetting from the upper face of a small rectangular fulcrum block 26 of insulating material. Midway the length of each of the said rail-clips between the side flanges 21 thereof I strike the metal 75 downward to form a spherically-contoured socket 27 provided with an axial clearance-passage 28 and adapted to receive a ball-ended sheet-metal cup 29 which in turn receives a bushing 30 of insulating material, 80 the upper end of which is formed with an annular flange 31 extending over the outwardly-turned annular flange 32 of the cup 29, which latter is also formed with an axial clearance-passage 33.

Extending axially through the insulating bushing 30 of each rail-clip and through the clearance-passages 28 and 33 aforesaid, as well as through clearance-slots 34 and 35 formed respectively in the side edges of the rail-supporting plate 13 and the flanges 12 of the tie 10, is the body-portion of an L-shaped tie-bolt 36, the lower laterally off-set end 37 of which is adapted to extend inward into the interior of the tie through either one of a pair of perforations 38 and 39 formed in the side walls 11 of the tie about midway the height thereof and to one side of the vertical center of the rail 19. It will be noted that a pair of perforations 38 and 39 is provided for each tie-bolt.

The upper end of each of the four tie-bolts 36 is threaded for the reception of a nut 40 which bears against the outer face of a washer 41, the inner face of which in turn bears 105 against the insulating bushing 30 aforesaid. By screwing down upon the respective nuts 40 of the four obliquely disposed tie-rods 36, the same will in turn pull downward upon the rail-clips 20 and thereby hold the rail firmly 110

against both vertical and lateral displacement upon the upper face of the insulating cushion-block 16.

It will be understood by reference to the drawings that four rail-clips 20 are employed, two of which are positioned over each of the outwardly-turned flanges 12 of the tie 10, and that of each pair of rail-clips one is disposed upon one side of the rail and the other upon the opposite side thereof. Beneath each rail-clip the flanges 12 and the opposite sides of the rail-supporting plate 13 are provided respectively with the clearance-slots 35 and 34 aforesaid, through which the respective tie-bolts 36 pass.

In the event that it is desired for any reason to change the angle of inclination of the tie-bolts 36, this may be effected by shifting the inwardly-offsetting ends 37 thereof from one to the other of the perforations 38 and 39 already described and by engaging various ones of the notches 22 in the rail-clips with the edge of the base 23 of the rail. The domical boss 25 of the insulating fulcrum-blocks 26 which fit within the upwardly-struck sockets 24 of the said clips will under all ordinary conditions prevent the displacement of the said blocks with respect to their complementary rail-clips.

I wish to call attention to the fact that by means of the construction above described, in which the tie-bolts 36 engage the side walls of the trough-shaped sheet-metal tie, not only is the rail firmly held in place but the rail-supporting plate is very largely relieved of the strains which would tend to displace it lengthwise of the tie. Furthermore, by extending the legs 17 of the supporting-plate downward into the tie, the transverse rigidity of the latter is so much enhanced as to practically preclude the possibility of its collapse.

I claim:

1. The combination with a rail and a trough-shaped sheet-metal tie disposed beneath the same; of a rail-supporting plate extending between the respective opposite side walls of the said tie; a combined insulating and cushion block carried by the said rail-supporting plate; and fastening-means independent of the said rail-supporting plate and connected to the side walls of the said tie for holding the said rail in place upon the said block; whereby the said rail-supporting plate is substantially relieved of strains tending to shift the same lengthwise with respect to the tie.

2. The combination with a rail and a trough-shaped sheet-metal tie disposed beneath the same; of a rail-supporting plate extending between the respective opposite side walls of the said tie and formed in its upper face with a shallow recess; a combined insulating and cushion block located in the said recess; and fastening-means independent of the said rail-supporting plate and connected

to the side walls of the said tie for holding the said rail in place upon the said block; whereby the said supporting-plate is substantially relieved of strains tending to shift the same lengthwise with respect to the tie.

3. The combination with a rail and a trough-shaped sheet-metal tie disposed beneath the same; of a rail-supporting plate extending between the respective opposite walls of the said tie and formed upon its opposite ends with integral flanges turned at a right angle with respect to it and projecting downward into the said tie; a combined insulating and cushion block carried by the said rail-supporting plate; and fastening-means independent of the said rail-supporting plate and connected to the side walls of the said tie for holding the said rail in place upon the said block; whereby the said supporting-plate is substantially relieved of strains tending to shift the same lengthwise with respect to the tie.

4. The combination with a rail and a trough-shaped sheet-metal tie disposed beneath the same; of a rail-supporting plate extending between the respective opposite side walls of the said tie and formed in its upper face with a shallow recess and upon its opposite ends with integral flanges turned at a right angle to it and projecting downward into the said tie; a combined insulating and cushion block located in the said recess; and fastening means independent of the said rail-supporting plate and connected to the side walls of the said tie for holding the said rail in place upon the said block; whereby the said supporting-plate is substantially relieved of strains tending to shift the same lengthwise with respect to the tie.

5. The combination with a rail and a trough-shaped sheet-metal tie disposed beneath the same; of fastening-means located on each of the opposite sides of the said rail and including rail-engaging clips and obliquely-disposed oppositely-sloping tie-bolts extending between the said clips and the side walls of the tie for securing the said rail to the tie.

6. The combination with a rail and a trough-shaped sheet-metal tie disposed beneath the said rail and formed in its side walls with sockets; of fastening-means located on each side of the said rail, including rail-engaging clips and obliquely-disposed oppositely-sloping tie-bolts engaging the said clips and the sockets in the side walls of the said tie for holding the said rail in place.

7. The combination with a rail and a trough-shaped sheet-metal tie disposed beneath the same and formed in its opposite side walls with perforations; of fastening-means located on each side of the said rail, including rail-engaging clips and obliquely-disposed oppositely-sloping L-shaped tie-bolts hooked at their lower ends into the perforations in

the said tie and engaged at their upper ends with the said clips for holding the said rail in place.

8. The combination with a rail and a trough-shaped sheet-metal tie disposed beneath the same and formed in its opposite side walls with sockets; of a rail-supporting plate extending between the respective opposite side walls of the said tie; a combined insulating and cushion block carried by the said rail-supporting plate; and fastening-means located on each side of the said rail and including rail-engaging clips and obliquely-disposed oppositely-sloping tie-bolts connected at their upper ends to the said clips and at their lower ends to the said sockets in the side walls of the said tie for holding the said rail in place upon the said block; whereby the said rail-supporting plate is substantially relieved of strains tending to shift the same lengthwise with respect to the tie.

9. The combination with a rail and a trough-shaped sheet-metal tie disposed beneath the same and formed in its opposite side walls with sockets; of a rail-supporting plate extending between the respective opposite side walls of the said tie and formed in its upper face with a shallow recess; a combined insulating and cushion block located in the said recess; and fastening-means located on each side of the said rail and including rail-engaging clips and obliquely-disposed oppositely-sloping tie-bolts connected at their upper ends to the said clips and at their lower ends to the said sockets in the side walls of the said tie for holding the said rail in place upon the said block; whereby the said rail-supporting plate is substantially relieved of strains tending to shift the same lengthwise with respect to the tie.

10. The combination with a rail and a trough-shaped sheet-metal tie disposed beneath the same and formed in its opposite walls with perforations; of a rail-supporting plate extending between the respective opposite side walls of the said tie; a combined insulating and cushion block carried by the said plate; and fastening-means located on each side of the said rail and including rail-engaging clips and obliquely-disposed oppositely-sloping L-shaped tie-bolts having their lower ends hooked into the said perforations in the tie and their inner ends engaged with the said clips for holding the

said rail in place upon the said block; whereby the said rail-supporting plate is substantially relieved of strains tending to shift the same lengthwise with respect to the tie.

11. The combination with a rail and a trough-shaped sheet-metal tie disposed beneath the same and formed in its opposite walls with perforations; of a rail-supporting plate extending between the respective opposite side walls of the said tie and formed in its upper face with a shallow recess; a combined insulating and cushion block located in the said recess; and fastening-means located on each side of the said rail and including rail-engaging clips and obliquely-disposed oppositely-sloping L-shaped tie-bolts having their lower ends hooked into the said perforations in the tie and their upper ends engaged with the said clips for holding the said rail in place upon the said block; whereby the said rail-supporting plate is substantially relieved of strains tending to shift the same lengthwise with respect to the tie.

12. The combination with a rail and a trough-shaped sheet-metal tie disposed beneath the same; of a rail-supporting plate extending between the respective side walls of the said tie; a combined insulating and cushion block carried by the said rail-supporting plate; rail-clips for holding the said rail in place upon the said block and formed at their outer ends with upwardly-struck pockets; fulcrum-blocks located beneath the outer ends of the said rail-clips and having bosses entering the sockets therein; and tie-bolts connecting the said clips to the said tie.

13. The combination with a rail and a trough-shaped sheet-metal tie disposed beneath the same; of a rail-supporting plate extending between the respective side walls of the said tie; a combined insulating and cushion block carried by the said rail-supporting plate; rail-clips for holding the said rail in place upon the said block and formed between their ends with downwardly-struck spherically-contoured sockets having axial openings; a ball-ended cup positioned in the socket of the said rail-clip; and a tie-bolt passing axially through the said socket and ball-ended cup and engaged at its lower end with the side walls of the said tie.

In testimony whereof, I have signed this specification.

FRANK G. METCALF.
